(57) **CLAIM**

The ornamental design for a hand piece, as shown and described.

DESCRIPTION

FIG. 1 is a perspective view of a hand piece showing the new design;

FIG. 2 is a left side elevational view thereof;

FIG. 3 is a top plan view thereof;

FIG. 4 is a right side elevational view thereof;

FIG. 5 is a bottom plan view thereof;

FIG. 6 is a back side elevational view thereof; and,

FIG. 7 is a front side elevational view thereof.

The broken lines are for illustrative purposes only and form no part of the claimed design.

1 Claim, 3 Drawing Sheets
